MILKING MACHINE HANGER

Leander F. Fasching, Winsted, Minn.

Application June 9, 1948, Serial No. 31,853

1 Claim. (Cl. 248—285)

1

The present invention relates to a novel and improved device or hanger for suspended-type milking machines, the same being such in construction that it is calculated to take the place of surcingles such as are currently used on a cow being machine milked.

More specifically, the invention has to do with an up-to-date highly practical hanger construction which lends itself to adequate and satisfactory use when adjustably clamped on a fixed portion of a dairy barn stall.

In carrying out the principles of the invention I have found it expedient and practicable to utilize a vertical member of a dairy barn stall as a suitable place to attach a milking machine hanger. Therefore, it is an object of the invention to provide a simple, reliable and efficient hanger which accommodates the cow and the attendant and which takes the form of an attachment which is readily suitable and applicable to the associated parts of the stated stall.

A further object of the invention is to provide an attachment-type hanger which is strong, reliable, easy to handle and which adapts itself to the various needs of each individual cow.

A further object of the invention is to provide a hanger which has facilities whereby it may be regulated in relation to the cow as to height, extended location of the primary machine hanger arm, which allows the latter arm to be appropriately tilted or angle for best results, a guard arm being embodied to prevent side movement of the cow during the milking step.

Briefly, the preferred embodiment of the invention is characterized by a U-shaped fixture, means swingably mounting said fixture on the chosen part of the stall, said fixture including a horizontal limb, a vertical shaft portion and an upper limb, the shaft portion being swingably and adjustably mounted, the first named limb serving to accommodate an extensible and retractable hanger arm and the upper limb serving to accommodate the aforementioned guard.

Other objects, features and advantages will become more readily apparent from the following description and the accompanying illustrative drawings.

In the drawings, wherein like numerals are employed to designate like parts throughout the views:

Figure 1 is an elevational view showing a hanger constructed in accordance with the invention and further showing the manner in which same is attached to a stall frame and how the suspended-type milking machine, in dotted lines, is hung for use.

2

Figure 2 is an enlarged perspective view showing the details of construction with requisite particularity.

Figure 3 is a section on the horizontal line 3—3 of Figure 2, looking in the direction of the arrows, the stall member being fragmentarily depicted, the vertical adjustment of the overall device appearing in dotted lines.

Figure 4 is a fragmentary elevational view based on Figure 1 and showing the clamping bands, tubular bearing and hanger fixture bodily adjusted from left to right to vary the verticality of the axis of oscillation of said fixture.

Referring now to the drawings by distinguishing reference numerals and accompanying lead lines and with reference first to Figure 1, the numeral 5 denotes one of the end frames of a dairy barn stall including an upright 6 and an L-shaped portion embodying a horizontal limb 7 and vertical limb 8 which is here used as a support for the invention. It is to be stated that some stall frames are not necessarily shaped along the lines of the one disclosed in Figure 1. However, the invention is satisfactorily attachable to most types. What is more, and as far as the invention is concerned, I am interested only in a fixed support to which the attachment is applicable, for example, the limb or support 8.

The invention is characterized by a substantially U-shaped fixture 9 whose central portion constitutes a shaft 10, whose lower arm 11 projects at an angle in relation to the shaft and support 8 and whose upper arm 12 is somewhat shorter and obliquely disposed. The shaft portion is provided with a shoulder 13 which rests rotatably upon the upper end of a tubular vertically elongated bearing 14. The shaft 10 is rotatable in the bearing and the bearing is detachably and adjustably mounted on the support 8. More specifically, the bearing is provided with outstanding screw-threaded studs 15 which pierce apertures in the central portions of duplicate clamping bands 16, said bands being fashioned to rotatably and slidably embrace the support 8. The band ends are connected by appropriate fastenings 17. The studs serve to accommodate assembling and clamping nuts 18. The hanger arm is tubular and denoted by the numeral 19 and is telescopically slideable on the limb 11. The left hand end of said arm terminates in a hanger hook 20 which serves to accommodate a suspension-type milking machine 21. A sleeve 22 is slideable on the limb 12 and has a set screw 22 for regulation and clamping purposes and the free end of the sleeve is curved and upturned as at 23

so that it will swing in the path of the frame member 7. It is obvious that by reason of the clamps 16 the entire hanger may be lifted and lowered in respect to the stall floor, whereby to place the hanger arm 19 and milking machine at the desired level, depending on the height of the cow being milked. By rotating the clamps in respect to each other around the axis of the support 8, the shaft 10 may be canted or cocked to an angle to properly tilt the limb 11 and consequently the hanger arm thereon. The guard sleeve 21 may be adjusted according to requirements of the cow and the attendant to limit and prevent side movement of the cow. The weight of the milking machine on the telescoping arm 19 serves to maintain said arm frictionally in the position to which it is adjusted. The entire hanger, including the parts described, except the bearing 14 and clamps 16 may be swung forward and out of the way, when not in use.

In addition to the above, I desire to point out that the tip 23 of the guard arm is curved in a manner shown with a view toward minimizing injury and discomfort to the side of a cow as will be evident from the drawings. Further, and as stated said tip 23 is turned diagonally up to properly coact with the frame structure 7 thus permitting the units to be parallel with said frame structure when in a forward out-of-use position. The guard arm also serves as a suitable stop when in the latter position. Further, the tip 23 need not necessarily rest against the side of the cow when the unit is in position for use. The cow may have up to four to six inches of side movement without ill effect on the milking unit operation or hanger. Again, as stated the main purpose of the guard arm is to prevent excessive side movement which might pull the milking machine off the hook 20. All frame members are used in rows and therefore the frame to the left side 40 of the cow prevents her from veering off to the left.

Changes in shape, size, materials and rearrangement of details and parts may be resorted to in actual practice, so long as they do not depart from the spirit of the invention or the scope of the appended claim, as is well understood.

Having described the invention, what is claimed as new is:

A cow stall attachment of the class shown and described comprising a tubular bearing adapted for vertical disposition in relation to a relatively fixed support, said bearing being provided with a pair of integral outstanding screw-threaded studs, a pair of clamping bands having intermediate apertured portions embracing said bearing, said studs extending through the apertures in the bands and being provided with assembling nuts connecting the bands with the bearing so that the latter may be firmly but detachably mounted on the stated support, a substantially U-shaped heavy duty fixture adapted to support a weighty suspension-type mechanical milking machine, said fixture comprising a shouldered vertical shaft portion mounted for rotation in said bearing with the shoulder resting on the bearing and further including a horizontal lower limb and an oblique-angled upper limb, a tubular arm telescopically mounted on said lower limb and terminating at its outer end in a hanger hook, and a guard sleeve slidably and adjustably mounted on the free end portion of said upper limb, the free end of said guard sleeve being laterally bent and said sleeve being provided with set screw whereby it may be adjustably fastened to said upper limb.
